WILLIAM G. KENDALL, OF NEWARK, NEW JERSEY.

REFILL FOR VANITY CASES.

Application filed April 23, 1923. Serial No. 634,076.

To all whom it may concern:

Be it known that I, WILLIAM G. KENDALL, a citizen of the United States, and a resident of Newark, in the county of Essex and State of New Jersey, have invented a new and Improved Refill for Vanity Cases, of which the following is a full, clear, and exact description.

The present invention relates to new and useful improvements in vanity cases and it pertains more particularly to a compact carrier therefor.

It is one of the primary objects of the invention to provide a new and novel construction whereby a compact carrier may be firmly retained within a vanity case.

It is a further object of the invention to construct the device in such a manner that the compact carrier may be readily removed from the vanity case after the compact has been used.

It is a further object of the invention to provide a construction of this character which will be practically invisible within the vanity case.

It is a still further object of the invention to provide a construction of this character in which the compact may be used without interference on the part of the mechanism.

With the above and other objects in view, reference is had to the accompanying drawings, in which—

Figure 1 is a perspective view of a vanity case in open position showing the compact carrier in the act of being discharged therefrom;

Figure 2 is a detail transverse sectional view showing the position of the several parts in their normal position.

Referring more particularly to the drawings, the vanity case comprises a box-like body portion 5, having a hinged cover 6 preferably provided with a mirror 7. The body portion 5 is formed with a flange 8 over which the cover fits, all of which construction is common to conventional types of vanity cases.

In carrying out the invention a strap 9 is pivotally mounted as at 10, on the hinge which forms the pivotal mounting of the cover 6, and such strap extends downwardly to the forward end of the box as indicated in Fig. 2. The free end of the strap is bent upwardly to provide an extension 11, which

extension has an offset end portion 12 and an angularly disposed extremity 13. This angularly disposed extremity 13 is adapted to be received within a notch 14 formed in the flange 8 of the body 5 of the vanity case. As more clearly shown in Fig. 2, the strap 9 has two inwardly bent portions 15 and 16, and said inwardly bent portions 15 and 16 are adapted to engage the flanged edge of a compact carrier 17, the compact being designated by 18. The offset portion 12 forms a projection or shoulder 19, which is adapted to engage beneath the flange 8 to maintain the strap 9 in locked position.

The device operates in the following manner:

When it is desired to place a compact in the vanity case 5, the strap 9 is positioned as shown in Fig. 2, and when the compact is inserted within the vanity case and forced downwardly, the peripheral edge of the compact carrier 17 will engage beneath the inwardly bent portions of the strap 9 and prevent accidental displacement of the compact carrier relative to the strap.

When it is desired to remove the compact carrier 17, after the compact 18 has been used, it is only necessary to engage the angularly disposed end 13 of the strap 9 with the finger or fingernail, and move the strap 9 to the position shown in Fig. 1, when the compact carrier 17 is free to be removed from the box. After the carrier 17 has been removed and it is desired to replace it with another compact and carrier the strap 9 is lifted to position within the vanity case body 5 and the compact carrier is forced to position as heretofore described.

In order to present a neat appearance, the compact carrier 17 is provided with transversely extending channels 20, or the like, and it is intended that the strap 9 be received within one of these channels in order that it may occupy a position flush with the outer face of the compact carrier 17. It is to be noted, however, that this channel is not necessary, and the compact could, if desired, rest upon the upper face of the strap 9.

From the foregoing it is apparent that the present invention provides a new and improved form of compact retainer for vanity cases, and that such retainer provides a construction by means of which the compact may be securely retained within

the vanity case, and, at the same time, readily removed therefrom if desired.

What is claimed is:

1. In a vanity case, a body, a strap extending transversely of the body and pivotally connected thereto, and a compact carried by said strap.
2. In a vanity case, a body, a strap extending transversely of the body and pivotally connected thereto, and a compact carried by said strap and frictionally supported thereon.
3. In a vanity case, a body portion, a hinged cover therefor, and a strap extending transversely of the vanity case and pivotally connected thereto by the hinge of the cover of said vanity case, said strap serving to support a compact within the vanity case and serving as means for ejecting the compact from the body of the vanity case.
4. A vanity case comprising a body, a hinged cover therefor, a strap hingedly connected to the hinge between the cover and
- the body, said strap having an angularly disposed end adapted to conform to the interior shape of the body of the vanity case to form means for preventing movement of the hinged strap about its pivotal point.
5. In a vanity case, a body provided in its upper edge with a notch, a hinged cover for said body, a hinge for connecting the cover to the body, a strap pivotally connected to said hinge, and an angularly disposed end formed on said strap and adapted to be received within the notch of the flange of the body.
6. In combination with a pair of box members hinged together and arranged to overlap one another, a member arranged to have a portion rest flat against the bottom of one of the box members and having a pair of upwardly extending parts, one of said parts being hingedly connected to the hinge of the box members and the other part coacting with the wall of the box member for retaining it in operative position.

WILLIAM G. KENDALL.
